US0D1103346S

(12) **United States Design Patent** (10) **Patent No.:** **US D1,103,346 S**
(45) **Date of Patent:** **** Nov. 25, 2025**

(54) **BATHROOM FIXTURE**

(71) Applicant: **Kohler Co.**, Kohler, WI (US)

(72) Inventors: **Drew Johnson**, Sheboygan, WI (US);
Tory Hayner, Howards Grove, WI (US)

(73) Assignee: **Kohler Co.**, Kohler, WI (US)

(**) Term: **15 Years**

(21) Appl. No.: **29/805,597**

(22) Filed: **Aug. 27, 2021**

(51) **LOC (15) Cl. 23-01**

(52) **U.S. Cl.**

USPC **D23/254**

(58) **Field of Classification Search**

USPC D23/238-242, 246-247, 249-257, 499;
D8/300, 307-308

CPC F16K 31/602; F16K 31/605; F16K 31/607;
E03C 1/02; E03C 1/04

See application file for complete search history.

(57) **CLAIM**

The ornamental design for a bathroom fixture as shown and described.

DESCRIPTION

FIG. 1 is a perspective view of the claimed design;
FIG. 2 is a front view of the claimed design shown in FIG. 1;

FIG. 3 is a side view of the claimed design shown in FIG. 1;

FIG. 4 is another side view of the claimed design shown in FIG. 1;

FIG. 5 is a top view of the claimed design shown in FIG. 1; and,

FIG. 6 is a bottom view of the claimed design shown in FIG. 1.

The broken lines in the drawings depict portions of the bathroom fixture that form no part of the claimed design.

1 Claim, 6 Drawing Sheets
